US0D1063386S

(12) **United States Design Patent** (10) **Patent No.:** **US D1,063,386 S**
(45) **Date of Patent:** **** Feb. 25, 2025**

(54) **STORAGE BIN WITH PATTERN**

(71) Applicant: **VOLVO CAR CORPORATION**, Gothenburg (SE)

(72) Inventor: **Patrik Müller**, Gothenburg (SE)

(73) Assignee: **Volvo Car Corporation**, Gothenburg (SE)

(**) Term: **15 Years**

(21) Appl. No.: **29/893,412**

(22) Filed: **May 30, 2023**

(30) **Foreign Application Priority Data**

Nov. 30, 2022 (EM) 015004835-0007

(51) **LOC (15) Cl.** **12-16**

(52) **U.S. Cl.**

USPC **D12/425**

(58) **Field of Classification Search**

USPC D3/304, 311, 312, 313; D12/415, 419, D12/424, 425, 426

CPC .. B60R 11/00; B60R 7/02; B60R 7/04; B65D 25/06

See application file for complete search history.

(57) **CLAIM**

The ornamental design for a storage bin with pattern as shown and described.

DESCRIPTION

FIG. 1 is a front view thereof;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a left perspective view thereof; and,

FIG. 8 is a right perspective view thereof.

1 Claim, 8 Drawing Sheets
